BICYCLE CHAIN GUARD

Viktor Schreckengost, Cleveland Heights, Ohio, assignor
to The Murray Ohio Manufacturing Co., Nashville,
Tenn., a corporation of Ohio

Filed Jan. 29, 1969, Ser. No. 15,561

Term of patent 14 years

Int. Cl. D12—14

U.S. Cl. D90—5

FIGURE 1 is a side elevational view of a bicycle chain guard showing my new design;

FIGURE 2 is a bottom plan view thereof;

FIGURE 3 is an elevational view of the side opposite that illustrated in FIGURE 1;

FIGURE 4 is a view in section taken along line 4-4 of FIGURE 3; and

FIGURE 5 is a view in section taken along line 5-5 of FIGURE 3.

I claim:

The ornamental design for a bicycle chain guard, substantially as shown and described.
